METHOD OF SEALING DISSIMILAR MATERIALS

Henry K. King, Cabin John, Md.

Application March 18, 1941, Serial No. 383,943

17 Claims. (Cl. 123—169)

(Granted under the act of March 3, 1883, as amended April 30, 1928; 370 O. G. 757)

This invention relates to the method of uniting dissimilar materials, and more particularly to the method of securing metal to porcelain or other ceramic material to form a pressure resistant gas tight seal. This invention opens up a new technique in the construction or manufacture of electrical appliances requiring a metallic conductive member to be sealed to an insulating carrier member. In many industrial products it is desirable to unite such dissimilar materials so that they may be held together strongly and with their surfaces in such intimate contact as to prevent the formation of voids allowing foreign material to accumulate therein, and also to prevent leakage of gas at the surface of contact.

In other uses such joints must permit good thermal transmission from the surface of one material to the surface of the other. Since this method is particularly useful in the construction of spark plugs, producing a product having advantages heretofore unattainable, I have described and illustrated as specific examples of my improved method the construction of several types of spark plugs, as well as the construction of a high voltage insulator, although it will be understood that many other articles may be united in construction by the process hereinafter defined.

Since my invention is particularly adapted for use in the construction or assembly of spark plugs, and since I have selected this specific embodiment as illustrative of my improved method, I shall discuss some of the advantages it offers in this art, heretofore practically unattainable. In the construction and assembly of spark plugs considerable difficulties have been encountered in securing the porcelain insulator to the outer metallic jacket of the plug so as to obtain a good gas-tight seal, since the outer metallic jacket must be clamped against the porcelain or other refractory insulator with sufficient pressure to insure a good gas-tight seal of the products of combustion at the pressures usually encountered in a high compression aircraft engine and under the conditions to which the plugs of such engines must be subjected.

In obtaining this seal by the prior art methods there is a great possibility that the porcelain insulator will crack under clamping process, whereby its insulating properties would be destroyed. The patent to Warner, 1,498,858, is illustrative of one of the methods proposed to obviate this possibility in construction. The method proposed by Warner has several inherent

disadvantages which are not present in the spark plugs constructed under the method to be described hereinafter. For example, in the type of construction illustrated, the forces applied indirectly to the porcelain through the metallic collar must be equalized so that compressive stresses will alone be set up in the porcelain, since any unequal distribution of such forces will set up resultant tensional stresses which may crack the porcelain.

This equalization of the forces between the porcelain and metal is attained by providing a conical surface at the upper and lower end of the sealing collar which receives the pressure from the clamping screw, transmitting it to the porcelain insulator. If the surfaces of the collar, jacket and screw are not uniformly even unequal forces will be set up in the insulator which consequently produce a resultant force setting up tensional stress in the insulator. Ceramic insulators are strong under compression but not under tension, therefore the insulator may crack. Furthermore, the metal and the porcelain have, in general, radically different coefficients of expansion and the metal collar will tend to expand away from the porcelain upon being heated to its operating temperature, whereby the seal will be destroyed. It is further noted that the metal collar is clamped only at the conical surfaces, therefore the cylindrical portion of the collar will buckle or be otherwise distorted as the collar expands. It should also be noted that this patentee has also failed to provide a satisfactory sealing means between the inner electrode and the porcelain insulator.

The spark plug constructed under the method set forth in the U. S. Patent to Furber, 1,186,568, is impracticable since the surfaces of the jacket and insulator cannot, under this method, be brought into such intimate contact to form a gas-tight seal over a wide temperature range without cracking the porcelain insulator. When the insulator and metal are united under the method set forth in the patent to Devers, 1,760,586, a more satisfactory seal is obtained without subjecting the insulator to any severe stresses. However, the seal of the electrode, as illustrated, would be unsatisfactory in practice.

It is, therefore, an object of my invention to provide a method of securing dissimilar bodies together so that the junction of the surfaces will form a gas-tight seal which will remain gas-tight throughout the range of operating temperatures, irrespective of the fact that the mate-

rials have radically different coefficients of expansion.

It is a further object of my invention to provide an improved method of assembly or manufacture of spark plugs by which a gas-tight seal between the insulator and the body is produced in which compressive stresses are alone set up in the insulator so that breakage of the insulator, due to sudden and severe changes in temperature, is substantially eliminated.

It is also an object of my invention to provide an improved method of joining the insulator to the outer metallic shell of spark plugs, so that their respective surfaces are in such intimate contact that the joint offers substantially no resistance to the transfer of heat from the insulator to the outer shell.

The further objects of my invention reside in the provision of a simple, inexpensive method for joining dissimilar materials, and in the new and improved products which are formed thereby.

With these and other objects in view, as well as other advantages not herein set forth that may be incident to the use of my improved method or the products produced thereby, the invention consists in combinations hereinafter claimed, with the understanding that several of the necessary steps constituting same may be varied within the scope of what is hereinafter defined in the appended claims.

In order to make my invention more clearly understood, I have shown in the accompanying drawing, means for carrying this invention into practical use, without limiting the application of said invention to the specific examples illustrated in the accompanying drawing, in which:

Fig. 1 is a longitudinal sectional view of a cylindrical hollow porcelain insulator of a spark plug which is to be assembled in accordance with my invention;

Fig. 2 is the same view of Fig. 1 after the material of Fig. 1 has been subjected to the first method step;

Fig. 3 is the same view of the materials of Fig. 2 as they appear at a later step in the process;

Fig. 4 is a longitudinal sectional view of the spark plug showing the insulator secured to the outer metallic jacket, in accordance with the invention;

Fig. 5 is a longitudinal sectional view of the finished product made by the method of my invention;

Fig. 6 is a longitudinal view of a shielded spark plug constructed in accordance with my invention;

Fig. 7 illustrates my invention as applied to the construction of a mica insulated spark plug;

Fig. 8 is a sectional view illustrating my invention as applied to mounting a metallic support in a high voltage insulator;

Fig. 9 is an exploded view illustrating a modification of the method embodying my invention as applied to the assembly of a spark plug illustrated in Figs. 1 to 3, inclusive; and

Fig. 10 is a longitudinal cross-sectional view of a further modification.

Referring now to the drawing, particularly Figs. 1 to 5, inclusive, showing my invention as applied to the assembly of a non-shielded spark plug whose component parts are illustrated therein, and comprise the cylindrical ceramic insulator shown in Fig. 1, which is provided with a longitudinal bore 12 adapted to receive and securely hold the electrode rod 13; and an outer

metallic jacket 11 into which the insulator 10 is adapted to be inserted. My invention is carried out by the process which comprises first coating the hollow cylindrical insulator 10 on both its inner and outer surface over an area at which the seal is to be formed, with a suitable preparation containing the metal to be used in the formation of the seal. The coated areas on the ceramic insulator, as indicated in Figs. 2 and 3 at 14 and 15, are of an exaggerated thickness and may be applied to the insulator by any of a number of processes, all of which at present appear equally effective. For example, the area at which the seal is to be formed, as indicated in Fig. 2, may be painted with a suitable colloidal solution of gold, platinum, silver or other metal and the metal then fused into the insulator at a high temperature. Instead of the colloidal solution, the metal may be applied directly in the form of a foil or leaf and then fused into the insulator at a high temperature; or the metal may also be applied directly to the insulator by "sputtering," "cathode spraying," "silvering," or such other process well known to the art. The method which I prefer to use is the colloidal solution method, in which the metal is fused onto the porcelain in much the same manner as it is in the art of applying gold or platinum decorations to china dinnerware. One important feature of my invention, as will be apparent presently, resides in the provision of the metal to both the inner and outer surfaces of the insulator.

After the thin metal coating has been applied by any of the processes outlined above, it is built up to the desired thickness by electroplating, fusing or other process which includes "sputtering," "metal spraying," "silvering," or by applying a metallic band to the inner and outer surfaces by means of an expanded and shrink fit, respectively, although I prefer to build up the metal to the desired thickness, as shown at 14a and 15a of Fig. 3, by means of an electro-plating process after the metal coating contained in the colloidal solution has been fused into place and allowed to cool. It may be desirable under some conditions to apply the first coat and also to build the metal up to its desired thickness by a single process such as "sputtering" or "spraying." Consequently, in Figs. 4 to 10, inclusive, I have illustrated the metallic band as being built up of a single metal. I have done this primarily for the sake of clearness in the drawing; however, if the same metal were to be applied under the different processes, it would be proper to indicate same by means of single hatching.

After the metal is built up to the desired thickness it is machined down to a precalculated inner and outer diameter, as shown in the dotted outline of Fig. 3. The insulator is now ready to be inserted into the metallic jacket 11 to form a gas-tight seal therewith. Before inserting the insulator and metallic bands into the metallic jacket 11, the inner diameter of the jacket is expanded by heating the jacket to a high temperature, and the diameter of the outer metallic band 14 is reduced by cooling the insulator. I prefer to cool the insulator by inserting it in liquid air or in carbon dioxide snow, although other processes may be used. The cooled insulator is then inserted into the heated metallic jacket and the assembly brought to a uniform temperature. The entire unit is now heated and the electrode rod 14 is cooled by the same process as

applied above, and the electrode rod 14 is inserted into the metalized bore 12. The entire unit of electrode rod 13, porcelain 10, metallic rings 14 and 15, and outer metallic jacket 11, are now effectively sealed together for all conditions to which the plug may be subjected, since they are now in intimate thermal contact and a sufficient temperature differential between these members cannot be produced to reverse the shrink fit process.

It should be understood that the step of cooling is not applied solely for the purpose of obtaining a maximum temperature differential which will never be attainable in practice, but also to place the insulated member under compression by causing the outer cylindrical ring 14 to be shrunk tightly about the insulator, so that when the insulator and jacket are both heated to provide for the insertion of the electrode rod 13, the metal band will not be expanded away from the insulator, and thereby destroy the effective seal between the band and insulator. This is one of the important distinguishing novel features of my invention, which has rendered satisfactory the products produced by this method, while the products produced under methods as outlined in the prior art with which I am familiar, have failed.

Furthermore, the inner ring 15 also serves a double function in that as the insulator and jacket assembly shown in Fig. 4 are heated to allow for the insertion of the cooled electrode, which has a greater coefficient of expansion than the porcelain insulator, the inner ring is thus expanded into intimate compressive contact with the insulator, so that compressive stresses are set up therein, whereby the seal will be preserved after the assembly attains the final temperature.

The metal used in forming the rings 14 and 15 is preferably a soft metal such as copper, which, under the compressive forces referred to above will be firmly pressed into the pores of the metallic jacket and the electrode and will be retained in its intimate contact with the porcelain by these compressive forces. The outer metallic ring 14 may also be thinly coated with a metal having a low melting point, such as tin or the like, so that as the operating temperature of the jacket and ring 14 is increased, this metal will become molten and will be forced into whatever interstices that may still exist between the band and the jacket. The joint between the band and the jacket may also be spot welded at the top of the band since the band and the insulator are under tension and can thus withstand the heat of the weld. From tests to which spark plugs constructed under the method herein presented have been subjected, it would appear that the provision of the coat of low melting point metal or the welds would be unnecessary. They may, however, be used merely as an added protection against gas leakage past the seal.

In actual construction the coefficients of expansion of all materials are known and the temperatures to which all parts are subjected are precalculated, so that compressive forces set up by the binding action of the inner and outer ring 14 and 15, respectively, are substantially balanced over the normal operating temperatures of the plug. To complete the spark plug structure, a spark point 16 is conveniently mounted on the jacket 11 and a suitable conductive button 17 is threaded into the body of the insulator 10. The binding nut 18 is threaded onto an end of the electrode rod so that the ignition cable may be secured to the plug between the button and the

binding nut to be in current conductive relationship with the electrode.

In Fig. 6 I have illustrated a radio shielded spark plug constructed by the method outlined above, and in this construction, in which similar reference numerals have been used to indicate similar parts, the outer jacket 11' has a longitudinal extended portion which completely surrounds the refractory insulator 10' and forms the shielding element therefor. The shielding element is provided with a threaded portion to which the ignition cable cap 19 may be removably secured. In this spark plug the shape and configuration of the insulator 10' is modified somewhat in accordance with the plug construction, and a plurality of spark points 16' are mounted on the jacket. Other plug details are similar to those illustrated in Fig. 5.

Fig. 7 illustrates this invention as applied to a mica insulated spark plug, having a unitary shell member comprising a shielding element 21 shown as an extension of the threaded base 22, there being an intermediate flanged portion 23 having the usual polygonal section 24, which receives the wrench or other tool for inserting the plug into the cylinder wall. The shielding portion is threaded to accommodate a cap similar to that shown in Fig. 6.

In the construction of this spark plug the hollow cylindrical refractory bushing 25 is provided with the metallic bands 26 and 27 on its inner and outer surface by any combination of the methods set forth above, and the refractory bushing and bands are secured to the shell member 20 by the same process outlined above. Furthermore, the electrode rod 28 is also inserted into the refractory insulator 25 by the process outlined above, whereby a tight seal between jacket, insulator and electrode is obtained. Around the lower part of the electrode rod 28 a stack of mica washers 29 is disposed which rest on shoulder 30 formed on the electrode, so as to press the stack of washers between the bushing 25 and said shoulder. Above the bushing 25 and surrounding the electrode rod 28 is a second stack of mica washers 31. The upper end is formed so as to compress the washers between the porcelain bushing and a washer 32 positioned over the upper end of the electrode.

In the past, considerable difficulty has been experienced with the porcelain type spark plug in service, by reason of the fact that under high temperatures the end of the porcelain insulator will chip away from the metallic electrode at its base which may, in time, cause the plug to fail. This chipping of the insulator is particularly noticeable where the spark plugs are used on aviation engines. Furthermore, lead fouling is more pronounced in the porcelain type of plug, with the result that the plugs unless frequently cleaned may in time be shorted out. The plug which I have illustrated in Fig. 7 is designed to overcome these disadvantages and at the same time retain the advantages of the porcelain insulator with the improved sealing means herein disclosed. The mica is capable of withstanding the excessively high temperatures of combustion and the lead fouling is less pronounced with mica than with porcelain.

In Fig. 8 I have shown my invention as applied to the construction of a high voltage pin type insulator. In the prior art these insulators were usually attached to the iron pins by screw threads in which the threaded portion of the pin is tapered downwardly from the top of the pin. A good fit in the threads between the pin and the

insulator is not commonly attained because the porcelain of the insulator warps in manufacture so that the hole ceases to be circular or the surface of the thread may not be smooth, consequently, in attempting to insert the pin, the insulators are frequently cracked. In order to avoid this the tread of the pin is usually made of lead or other soft metal, but even this is unsatisfactory, since the insulators become loose with changes in temperature, due to the different coefficients of expansion. The construction by the method involved in my invention has overcome many of these disadvantages.

The body of the insulator 48 is provided with a metallic tension band 41, formed around the base of the insulator. This band 41 may be placed on in accordance with the process involved in my invention, although care must be exercised in placing this band on the insulator so that its expansion will not set up excessive tensile stresses in the insulator. It is preferable to provide a clearance between the outer surface of this band and the body of the insulator as illustrated in Fig. 8. In the process of assembly I first coat the inner surface of the pin hole 42 with a colloidal solution of the metal which is to be used. This metal is then fused into the insulator at a high fusing temperature, after which the metallic coated insulator is allowed to cool. I then proceed to build up the metal to the desired thickness by electroplating or other equivalent process which I have set forth above. The metal is then machined to the pre-calculated inner diameter. The outer tension ring 41 is preferably applied after the insulator has been heated, but may be built up under the process defined above if suitable clearance is provided to allow the band to expand without transmitting excessive tensile stresses to the outer surface of the insulator. The insulator and metallic bands are now heated to a precalculated temperature to expand the inner diameter of the metallic lined pin recess and the pin 43 is cooled down by being immersed in liquid air or carbon dioxide snow, and is inserted into the insulator, which upon attaining final temperature produces a tight joint.

It should be again noted that the inner band is expanded into a binding relationship with the insulator so that compressive stresses are set up therein and the band 41 also sets up compressive stresses in the opposite direction so as to prevent any breakage during the construction process, and to equalize the forces of the inner band.

In the modification shown in Fig. 9, a soft metallic band 48 is applied directly to the metallic shell 46, preferably by a shrink or expanded fit process so that the band is stressed at normal temperatures. The band and shell 48 and 46 are now heated to expand the inner diameter and the coefficient of expansion of the two metals are selected so that the expansion of the inner band is greater than the outer shell, so that a tight seal is at all times maintained. The porcelain insulator 47 is now cooled down by being placed in liquid air or carbon dioxide snow and inserted into the expanded metal shell.

The electrode rod 48 has a metallic band of soft metal 49 secured thereto by a shrink process or any other applicable method, and this electrode rod after being cooled is inserted into the expanded insulator and shell assembly. Upon attaining the final temperature, the soft metal of the inner and outer band is forced into inti-

mate contact with the porcelain, forming an exceedingly tight seal.

As is apparent from Figs. 1 to 6, inclusive, difficulties may be experienced in attempting to apply the metallic coating to the inner surface of the insulator because of the restricted bore 12, and in order to avoid such difficulties in construction I have devised and illustrated in Fig. 10 a modified form of a shielded spark plug, constructed under the process involved in my invention, as set out above, in which the diameter of the bore 51 of the insulator 50 is materially increased so that the metallic coating 15 formed on the inner surface of the porcelain insulator 15 may be easily applied and confined to that area over which the seal is to be formed. The insulator 50 is also provided with an outer metallic band 14 which is applied by any of the processes outlined above.

The outer metallic shell 52 is heated to a predetermined temperature and the cooled insulator with bands 14 and 15 is inserted therein. The inner electrode 53 has an integrally formed middle portion 54 having an increased diameter. This electrode is cooled down and inserted into the heat expanded metallic jacket, insulator, and bands so that the electrode will form a seal with the inner band at the outer surface of the cylindrical portion 54. The outer jacket is also provided with an ignition cable cap 55 threadably secured to the metallic shell 52. The cable conductor is embedded in any suitable insulating material 56 and is connected to the electrode rod 53 by means of a coiled resilient electrically conductive member 57. It is thus apparent that the plug which I have disclosed would be easier to manufacture than the plug illustrated in Fig. 6, and still retain many of the advantages of this type of spark plug.

Other modifications and changes in the number and arrangement of the parts may be made by those skilled in the art without departing from the nature of the invention, within the scope of what is hereinafter claimed.

The invention described herein may be manufactured and/or used by or for the Government of the United States of America for governmental purposes without the payment of any royalties thereon or therefor.

Having thus set forth and disclosed the nature of this invention, what is claimed is:

1. In the manufacture of a spark plug, the method of mounting and sealing the ceramic insulator in the outer metallic jacket of the spark plug which comprises, the steps of applying a thin coating of metal to the ceramic insulator so that it may be in intimate contact with the ceramic material, building up the coated area with a metal to form a tension band thereabout, shaping the outer surface of said metallic band to the precalculated dimensions, expanding the inner diameter of said jacket, contracting said band so that compressive stresses are set up in the ceramic material and the seal between the band and ceramic is tightened, and inserting the insulator into the plug jacket, whereby a gas-tight seal will be formed between the surfaces of the metallic shell and the surface of said insulator.

2. The method of uniting parts of dissimilar materials, wherein part of one material is to be inserted into a socket formed in the other material which includes, the steps of plating one of said materials with a thin coating of metal,

building up said metal to a desired thickness, to form a tension band about said one of said materials, shaping said band to a precalculated diameter, heating the material in which the socket is formed so as to expand the same to increase the socket diameter, and cooling said material which is to be inserted into said socket, whereby the binding action of said tension band will be increased either by the heating or cooling process to subject one of said parts to compressive stress, and finally inserting said one part of one material into the socket formed into the other material so that a gas-tight seal is formed at the junction of the two parts.

3. In the manufacture of a spark plug the method of securing the ceramic insulator to the outer metallic jacket, which comprises the steps of forming a tensioning band around the ceramic insulator, heating the outer jacket to expand same increasing its inner diameter, cooling the 15 ceramic insulator and tensioning band to contract the band, whereby its tensional stresses will be increased and compressive stresses will be set up in the insulator, and inserting the cooled ceramic insulator and band into the heated expanded jacket so that a gas-tight seal will be formed at the union of their two surfaces.

4. In the manufacture of a spark plug, the method of mounting and sealing the ceramic insulator to the outer metallic jacket and of mounting and sealing the electrode rod to the longitudinal bore formed in said insulator which comprises the steps of, plating the inner and outer surface of said ceramic insulator with a thin metallic coat formed in intimate contact therewith, building up the coated areas with a suitable metal so as to form metallic bands of a desired thickness, heating said outer jacket to expand same increasing its inner diameter, and cooling said ceramic insulator and bands so that the outer band will bind the insulator to increase the tightness of the seal and subject said ceramic to compressive stresses, inserting said insulator into said jacket, heating the insulator and jacket to expand the inner metallic band and prevent the hollow insulator from being subjected to compressive stresses caused by the shrinking of the outer metallic jacket prior to the insertion of said electrode, and to cause the inner band to expand to balance out the compressive forces of said insulator and increase the tightness of said inner seal, cooling said electrode rod, and inserting said rod into the bore formed in said insulator.

5. In the manufacture of a spark plug, the method of uniting parts including an electrode, ceramic insulator and metallic jacket to form a gas-tight seal therebetween which consists in tightly securing a band of soft metal around the central electrode, placing a band of soft metal around the inner surface of said metallic jacket so that a tight seal is formed between the band and jacket, heating the jacket and inner band to expand its inner diameter, cooling the ceramic insulator which has a longitudinal bore formed therein, inserting the insulator into the heated jacket, heating the insulator and metallic jacket to a uniformly high temperature so as to expand the insulator increasing the diameter of said longitudinal bore and setting up compressive 70 stresses therein, cooling the central electrode and band and inserting it into the longitudinal bore, whereby the insulator will be subjected to an inner and outer radial force when the assembly attains uniform temperature, increasing the seal 75

between parts and setting up compressive stresses in said insulator.

6. The method of securing two metallic sealing bands to the inner and outer surfaces respectively of an insulator having a longitudinal bore therethrough, which includes the steps of heating said outer band to expand same, cooling said insulator to contract same, inserting the insulator into said outer band, heating the outer band and insulator to a uniform temperature to expand the insulator increasing the diameter of said longitudinal bore and setting up compressive stresses therein, cooling the inner band to contract same and inserting the inner band into the expanded longitudinal bore formed in the insulator, whereby the contracted outer band and expanded inner band will exert balanced radial forces on the inner and outer surface of the insulator, setting up compressive stresses only therein.

7. The method of sealing the insulator and bands as constructed in accordance with the method set forth in claim 6, to a metallic jacket which comprises cooling the insulator and bands and heating the metallic jacket, and inserting the insulator and bands into the metallic jacket so that a seal is formed at the union of the outer band and jacket.

8. In a spark plug, the combination of an outer metallic jacket, a hollow cylindrical insulator positioned within said jacket and formed of a material capable of withstanding severe compressive stresses only, said insulator being provided with a longitudinal bore extending therethrough, a central electrode positioned within the hollow bore, means comprising an expanded and shrunk fit between the inner surface of said metallic jacket and said insulator and between the inner surface of said insulator and said electrode for sealing the insulator to said jacket and to said electrode whereby said insulator will be subjected to substantially balanced inner and outer radial forces so that compressive stresses alone will be set up therein.

9. The invention as defined by claim 8, where in said last named means comprises a contracted outer metallic band and an expanded inner metallic band.

10. In the method of manufacture of a spark plug having a hollow porcelain insulator which includes the steps of applying a thin coating of metal to the inner and outer surface of said insulator, building up the coated area with a metal so as to form an inner and outer metallic band, and machining the inner and outer band to pre-calculated dimensions.

11. In an apparatus of the class described, an insulating material capable of withstanding severe compressive stresses only having a bore formed therein, an inner expanded metallic band formed in said bore, an outer compressive metallic band formed about said insulator radially opposite said inner band, and means for applying said inner and outer band to said insulator so that radial forces will be transmitted from the band to the insulator, the stresses transmitted to said insulator by the binding action of said outer band being equal to or greater than the stresses transmitted to the insulator by the inner band so that compressive stresses only will be set up in said insulator.

12. In a spark plug, a body having a cylindrical bore forming a shell, a hollow cylindrical ceramic insulator bushing secured within the bore of said shell so as to form a gas-tight seal therewith, a

metallic electrode having a shoulder formed near its tip end sealed within said insulator bushing, and a plurality of laminated mica washers positioned about said metallic electrode between the shoulder formed on the tip end of said electrode and said ceramic insulator, whereby a long leakage path is provided from the tip end of the electrode to the metallic shell which is less susceptible to lead fouling than the porcelain bushing through which the electrode is sealed to said shell.

13. A spark plug for internal combustion engines comprising a tubular ceramic insulator having a thin metallic film formed at diametrically opposed areas on the inner and outer surface of said insulator respectively, said films being fused into the body of said insulator, a metallic jacket surrounding said insulator opposite the coated area provided with said outer film, a metallic electrode disposed within the bore of said tubular insulator, means comprising an inner expanded metallic ring for sealing said electrode to said insulator at the inner surface area over which the metallic film has been applied, and means comprising an outer metallic shrunk ring for sealing said metallic jacket to said insulator at the outer surface area over which the film has been applied whereby the metal of the expanded and shrunk rings will be pressed into intimate contact with the inner metallic film and electrode, and outer metallic film and jacket respectively to form a gas-tight seal.

14. A spark plug for an internal combustion engine comprising a tubular ceramic insulating member, a metallic jacket surrounding said insulating member, a metallic electrode having a shoulder formed near its tip end positioned within said insulating member, a plurality of laminated mica washers positioned about said electrode between the shoulder formed on the tip end of said electrode and said insulating member so that a long leakage path is provided from the tip end of the electrode to the metallic jacket which is less susceptible to lead fouling and chipping than is the ceramic insulator, means sealing said electrode to said insulating member exerting an

outwardly directed radial force on said insulating member, and means sealing said insulating member to said jacket exerting an inwardly directed radial force on said insulating member.

15. A spark plug for internal combustion engines comprising a tubular ceramic insulating member, a metallic jacket surrounding said tubular member, a metallic electrode disposed within the bore of said tubular member, means sealing said electrode to said member exerting an outwardly directed radial force on said member and means sealing said metallic jacket to said member exerting an inwardly directed radial force thereon, the inwardly directed radial force being equal to or greater than the outwardly directed radial force throughout the thermal range of operation of said spark plug whereby said ceramic insulating member will be subjected to compressive stresses only.

16. The invention as defined in claim 15 wherein said first named means comprises an expanded inner metallic band positioned between said electrode and inner surface of said insulating member, and said last named means comprises an outer shrunk band positioned between the inner surface of said metallic jacket and the outer surface of said electrode.

17. In the method of uniting parts of dissimilar materials wherein one of said materials is to be inserted into a socket formed in the other material, said other material being capable of withstanding severe compressive stresses only, which includes the steps of forming an outer metallic band about said socket, forming an inner metallic band within said socket diametrically opposite said outer band, heating said other material and bands to expand the inner diameter of said inner band and to set up compressive stresses in said other material, cooling said first named material to contract same, and inserting said first named material into the socket formed by the inner band formed in said other material whereby the other material between said inner and outer bands will be subjected to compressive stresses only throughout the temperature range of operation.

HENRY K. KING.
